UNITED STATES PATENT OFFICE.

WADE H. ASHER, OF SELMA, CALIFORNIA, ASSIGNOR OF ONE-HALF TO HARRISON HAMPTON, OF SAN ANTONIO, TEXAS.

FRUIT CUTTER.

Application filed July 26, 1924. Serial No. 728,400.

To all whom it may concern:

Be it known that I, WADE H. ASHER, a citizen of the United States, residing at Selma, in the county of Fresno and State 5 of California, have invented a new and useful Fruit Cutter, of which the following is a specification.

This invention relates to a device designed to facilitate the hand-picking of fruit such 10 as grapes, apples, pears or the like to insure against bruising the fruit when removing it from the stem.

Another important object of the invention is to provide a device of this character which 15 will be readily positioned on the hand of the user, the construction being such as to be held in position by the natural bend of the index finger, obviating the use of securing straps or gloves commonly employed for 20 securing knives or the like to the hands of the user.

Another object of the invention is the provision of a removable blade so that the 25 blade may be readily and easily removed for repair or replacement.

With the foregoing and other objects in view which will appear as the description proceeds, the invention resides in the combination and arrangement of parts and in 30 the details of construction hereinafter described and claimed, it being understood that changes in the precise embodiment of the invention herein disclosed, may be made within the scope of what is claimed, without departing from the spirit of the 35 invention.

Referring to the drawings:

Figure 1 is a perspective view of a hand 40 disclosing a device constructed in accordance with the invention as positioned thereon.

Figure 2 is a plan view of the device.

Figure 3 is a sectional view taken on line 3-3 of Figure 2.

Referring to the drawing in detail, the 45 device includes a substantially tubular body portion 5 which has a portion thereof cut

away to provide an opening or clearance for the knuckle of the fore-finger when the body portion is properly positioned on the hand of the user. 50

As shown by Figure 2 of the drawing, the body portion is curved longitudinally so that the curvature of the body portion will conform to the curvature of the inner finger of the user supporting the device. 55

A ring member indicated at 6 has swivel connection with the body portion 5 at 7 and is designed to receive the second finger of the hand of the user to brace the device against twisting on the fore-finger when in use. 60

As clearly shown, the body portion is formed with a recessed portion 7 adapted to accommodate the blade 8 which is provided with openings to accommodate the securing screws 9 that pass through the blade and are 65 embedded in suitable threaded openings provided in the body portion.

The blade is provided with teeth 10 adapted to readily cut the stem of the fruit being picked, eliminating any possibility of 70 bruising the fruit while the same is being gripped by the hand of the picker.

It is believed that in view of the foregoing detail description, a further detail description as to the operation of the device is 75 unnecessary.

I claim:

A fruit stem cutting device comprising a curved body portion, the body portion adapted to engage the under surface of the fore-finger of the hand of the user throughout substantially the entire length of the finger, the upper portion of the body portion being cut away to provide a clearance for the knuckle of the fore-finger, a blade carried 85 by the body portion, a ring member adapted to be positioned over a finger of the hand of the user, and means for pivotally connecting the ring member to the body portion.

In testimony that I claim the foregoing as 90 my own, I have hereto affixed my signature.

WADE H. ASHER.
